UNITED STATES PATENT OFFICE

2,477,944

ADJUSTABLE PITCH PROPELLER

Edward H. Rouse, Minneapolis, Minn.

Application July 19, 1947, Serial No. 762,046

8 Claims. (Cl. 170—135.75)

1

My invention relates to adjustable pitch propellers and has for an object a propeller which can be easily adjusted.

Another object of the invention resides in constructing the propeller with a hub having a blade pivoted thereto, the pivot for said blade being disposed so that swinging of the blade changes the pitch of the same and in providing an adjusting member therefor situated at the rear end of the blade and readily accessible for manipulation.

An object of the invention resides in mounting said adjusting member for rotation about the axis of said hub.

A still further object of the invention resides in constructing the blade with a part movable radially upon swinging of the blade and in providing the adjusting member with a juxtaposed part adapted to be engaged by the radially movable part of the blade to limit the swinging movement of the blade.

Another object of the invention resides in providing one of said parts with an abutment and the other of said parts with a number of stops, each stop being located a different distance from the axis of the hub and preferably in the form of a spiral, said stops upon rotation of the adjusting member being adapted to be separately brought into position for engagement with said abutment.

An object of the invention resides in providing yieldable locking means for holding the adjusting member in adjusted position.

A still further object of the invention resides in providing a driven shaft on which said hub is mounted and in constructing said adjusting member in the form of a collar rotatable thereon.

A feature of the invention resides in providing locking means for said collar including engageable teeth on said collar and hub for holding the collar in adjusted position, and in further providing resilient means acting between said shaft and collar for urging said teeth into engagement.

Another object of the invention resides in rotatably mounting said hub on said shaft and in providing releasable driving means between said shaft and hub and including a driving element and a driven element having facing surfaces formed with engageable teeth thereon.

An object of the invention resides in utilizing the spring employed in connection with the locking means for rendering said driving means effective.

Other objects of the invention reside in the novel combination and arrangement of parts and

2

in the details of construction hereinafter illustrated and/or described.

In the drawings:

Fig. 1 is a longitudinal elevational part-sectional view of a propeller and a portion of a propeller shaft illustrating an embodiment of my invention.

Fig. 2 is a rear end view of the structure shown in Fig. 1 with portions of the same broken away to illustrate the construction of the propeller.

Fig. 3 is a perspective view of the parts of the invention separated from one another and shown partly in section.

Fig. 4 is a cross-sectional view taken on line 4—4 of Fig. 1.

Fig. 5 is a view similar to Fig. 4 showing the parts in altered position.

Fig. 6 is a view similar to Figs. 4 and 5 showing the parts in still different positions.

Fig. 7 is a cross-sectional view taken on line 7—7 of Fig. 1.

In the use of out-board motors, it has been found that the propeller operates most efficiently with the blades set at a certain pitch. This pitch varies for different load conditions and speeds. In addition, it has been found that propellers frequently strike submerged objects and that the usual shear pins employed therewith are broken thus necessitating removal of the propeller and installation of a new pin. Devices for overcoming these difficulties require a considerable amount of space making a clumsy and awkward construction and in the case of adjustment of the pitch of the propeller, necessitate swinging out the blades before the adjustment can be made. The instant invention provides a construction whereby both of the problems involved may be solved with a simple and compact construction which may be easily adjusted.

The propeller illustrated is indicated in its entirety by the reference numeral 10 and comprises two blades 11 and 11a pivoted to a hub 13. The propeller 10 is mounted upon a propeller shaft 14 which is driven from the motor through gearing or other transmission elements such as are well known in the art and which are not shown in the drawings. The various parts of the structure shown will now be described in detail.

The shaft 14 has a uniform diameter throughout the intermediate portion 12 of its extent and is formed with a reduced portion 15 at the rearward end of the same which is threaded to receive a nut 16. The hub 13 has a boss 19 formed on it and which is provided with a bore 17 of such dimensions as to provide a bearing for rotatably

and slidably supporting said hub on the portion 12 of shaft 14. The hub 13 is constructed with two lugs 18 and 18a which are disposed on opposite sides of the boss 19.

Inasmuch as both blades 11 and 11a are of the same construction, only the blade 11 will be described in detail. However, the same reference characters to which the suffix "a" have been added will be used to designate the corresponding parts. The blade 11 is shown in detail in Fig. 7 and is constructed with a yoke 21 extending partly about the boss 19 and straddling the lug 18. This yoke includes two arms 22 and 23 which are disposed on opposite sides of said lug. A pin 24 extends jointly through said arms and through said lug 18 and serves to pivot the blade for swinging movement from a position such as shown in full lines in Fig. 1 to a position as shown in dotted lines in said figure. As the blade moves from one position to the other, the pitch of said blade varies and by limiting the position to which the said blade may swing, the pitch at which the blade operates can be determined.

For the purpose of effecting a drive between the shaft 14 and the hub 13, a releasable clutch 25 is employed. This clutch includes a driving element 26 and a driven element 27. The latter element is formed as part of the hub 13 being in the nature of a skirt extending forwardly from the boss 19 thereof. This skirt has a conical surface 28 which is formed with a number of radially extending teeth 29. The driving element 26 is in the form of a figure of revolution having a conical surface 31 adapted to engage the surface 28 of the element 27. This surface has formed thereon, a number of teeth 32 which are adapted to mesh with the teeth 29 when the element 26 is urged against the element 27. The element 26 has a bore 33 through the same and through which the shaft 14 extends. A pin 34 extends through the shaft 14 and is received in a socket 35 formed in the element 26. This pin serves as a key for restraining rotation between the driving element 26 and the shaft 14 and effecting a drive therebetween. The contour of the teeth 32 and 29 is curved so that when undue pressure is applied to one of the blades, the said teeth may slip out of mesh with one another in a manner to be presently described in detail and permit of relative rotation between the clutch elements.

The blade 11 is constructed with an abutment 36 which is located at the rearward end of said blade and which extends inwardly toward the shaft 14 and is considerably spaced therefrom. This abutment has a circular surface 37 which is concentric with the axis of the said shaft. Operating in conjunction with the two blades 11 and 11a is an adjusting member 38 which is rotatably mounted on the rearmost end of the shaft 14 and which is normally separated from the nut 16 by an intervening space 39. The said adjusting member is in the form of a collar and has an exposed surface 41 which is knurled or otherwise made rough to permit of manually engaging the same and rotating the said collar with respect to the shaft 14. The said collar has a bore 42 through which the shaft 14 extends and by means of which the said collar may rotate and operate upon said shaft. The rearmost end of the bore 42 of collar 38 is enlarged to form a cavity 43 concentric with the axis of the shaft 14. This provides a shoulder 44 at the foremost end of the said cavity. A compression coil spring 45 encircles the shaft 14 and is received within the cavity 43. This spring is seated at one end against the shoulder 44 and at

its other end against the underside of the nut 16. The spring 45 normally urges nut 16 away from the collar 38 tending to force the said collar toward the boss 19 of the hub 13.

At the forward portion of the collar 38 is formed thereon, a number of stops 46, 47, 48, and 49. These stops have cylindrical surfaces 51 which are concentric with the axis of the shaft 14. The said stops are located different distances from the axis of the shaft 14 and the surfaces 51 thereof are progressively arranged to jointly form a surface spiraling inwardly toward the axis of the said shaft. The stops 46, 47, 48, and 49 are adapted to be moved into a position for engagement with the abutment 36. When the adjusting member 38 is in the position shown in Fig. 4, abutment 36 may engage the stop 46 and the blade 11 may then swing to its fullest extent, as shown in full lines in Fig. 1. When the adjusting member 38 is rotated so that the same occupies the position shown in Fig. 5, the stop 47 is in position to be engaged by the abutment 36 and limits movement of the blade to a position forwardly of that shown in dotted lines in Fig. 1, but rearwardly of that shown in full lines in said figure. When the adjusting member 38 is moved to the position shown in Fig. 6, the stop 48 is in position to be engaged by the abutment 36. The parts may be so constructed that only a limited very small movement of the blade is possible at such location of the adjusting member or so that the blade is held immovable in its foremost position as shown in dotted lines in Fig. 1.

For holding the adjusting member 38 in adjusted position, the foremost end of the same is constructed with teeth 52 which are adapted to engage corresponding teeth 53 formed on the rearward end of the boss 19 of hub 13. Spring 45 serves to urge these two portions of the hub and adjusting member together and thereby holding said teeth in mesh restraining relative rotation between said adjusting member and hub. These teeth 52 and 53 are, however, curved in form and permit of rotation of the said adjusting member 45 when appreciable force is applied to rotate the same.

While the functioning of the propeller has been described in conjunction with one blade only, it will be comprehended that the other blade has 50 a corresponding abutment and that the adjusting member has another set of stops cooperating therewith so that both blades at all times occupy similar positions and function in the same manner.

Inasmuch as the spring 45 acts on the nut 16 mounted on shaft 14 and indirectly on the hub 13 through the adjusting member 38, it will be comprehended that the said spring serves a dual purpose. In the first instance, it causes the clutch element 26 to become engaged with the clutch element 27 and to effect a drive between the drive shaft 14 and the hub 13. In the second place, it urges the adjusting member 38 into engagement with the hub 13 and restrains rotatable movement of the same. This serves to hold the adjusting member in fixed position relative to said shaft with one or the other of the stops 46, 47, 48 and 49 in engagement with the abutment 36. However, relative rotation may be had between the hub and shaft or the hub and adjusting member when sufficient force is applied thereto.

The method of using the invention is obvious. The propeller is mounted on the propeller shaft as shown in the drawings. The adjusting member 75 normally remains in one of its adjusted positions

and the forward swinging movement of the blades is limited to the movement afforded when the abutment 36 engages one of the stops on the adjusting member. If another pitch is desired, the motor is stopped and the adjusting member 38 rotated by means of the knurled portion of the same until the proper stop is in position to be engaged by the abutments on the blades. The spring 45 then holds the same in adjusted position. If during operation of the motor, the blade strikes an object, the pressure on the blade forces the teeth 32 out of engagement with the teeth 29 and allows the clutch to slip. As soon as the force is removed, the clutch elements become immediately engaged and the drive is again effected between the driving shaft and the propeller hub.

The advantages of the invention are manifest. The device is extremely simple in construction and the hub thereof is compact and of small dimensions so that for a given diameter of blade, a suitable radial length of blade may be procured. The adjusting member is at the rearward end of the propeller where the same is readily accessible for the purpose of adjusting the propeller. A simple rotation of the same is all that is necessary and when released, the adjusting member becomes automatically located in its adjusted position. In the event that the blade strikes a submerged object, the blade is momentarily disengaged from the driving shaft. However, upon passing the object when the blade is again free, a driving connection is again effected between the shaft and the blade without requiring the installation of a new shear pin.

Changes in the specific form of my invention, as herein described, may be made within the scope of what is claimed without departing from the spirit of my invention.

Having described my invention, what I claim as new and desire to protect by Letters Patent is:

1. In a propeller, a driving member, a driven member and blades pivoted to said driven member, a clutch having a clutch element carried by said driven member and another clutch element carried by said driving member, said elements upon relative axial movement becoming engageable, an adjusting collar carried by said driving member and rotatably and slidably mounted thereon, said collar holding said blades in various adjusted positions and resilient means acting between said collar and driving member and urging relative axial movement therebetween to urge said clutch elements in engagement and said collar in adjusted position.

2. In a propeller, a driven shaft, a hub rotatably and axially movable on said shaft, blades pivoted to said hub, the pivots of said blades being positioned so that the pitch of the blades varies upon swinging of the blades, said blades each having an abutment moving radially upon swinging of the blades, a collar rotatable and movable axially relative to said shaft and having stops for engagement with said abutments to hold the blades in adjusted position, a clutch having an element fixed relative to said shaft and an element carried by said hub, said elements becoming engaged upon relative axial movement between said shaft and hub and a spring acting between said shaft and collar and urging relative movement therebetween to hold said collar in adjusted position and said clutch in engagement.

3. In a propeller, a driven shaft, a hub rotatably and axially movable on said shaft, blades pivoted to said hub, the pivots of said blades being positioned so that the pitch of the blades varies

upon swinging of the blades, said blades each having an abutment moving radially upon swinging of the blades, a collar rotatable and movable axially relative to said shaft and having stops for engagement with said abutments to hold the blades in adjusted position, a clutch having a clutch element formed in said hub and another clutch element fixed relative to said shaft, said clutch elements being engageable upon axial movement of the hub relative to the shaft, a spring acting between said shaft and collar and urging said collar against said hub and said hub toward said clutch element on said shaft to cause the collar to engage said hub and said clutch elements to be engaged.

4. In a propeller, a driven shaft, a hub rotatably and axially movable on said shaft, blades pivoted to said hub, the pivots of said blades being positioned so that the pitch of the blades varies upon swinging of the blades, said blades each having an abutment moving radially upon swinging of the blades, a collar rotatable and movable axially relative to said shaft and having stops for engagement with said abutments to hold the blades in adjusted position, a clutch having a clutch element formed in said hub and another clutch element fixed relative to said shaft, said clutch elements being engageable upon axial movement of the hub relative to the shaft, a shoulder formed on said collar, a nut mounted on the end of said shaft and a spring acting between said nut and shoulder and urging said collar against said hub and said clutch elements into engagement.

5. In a propeller, a driven shaft, a hub rotatably and axially movable on said shaft, blades pivoted to said hub, the pivots of said blades being positioned so that the pitch of the blades varies upon swinging of the blades, said blades each

40 having an abutment moving radially upon swinging of the blades, a collar rotatable on said shaft and having a pair of stops extending for a portion of the circumferential extent thereof for engagement with said abutments, said collar when rotated to one position bringing said stops into positions to be engaged by said abutments to hold the blades at one particular pitch and when rotated to another position moving said stops out of the path of movement of said abutments to allow said blades to swing in a manner to have a different pitch and locking means for holding said collar from rotation.

6. In a propeller, a driven shaft, a hub rotatably and axially movable on said shaft, blades

55 pivoted to said hub, the pivots of said blades being positioned so that the pitch of the blades varies upon swinging of the blades, said blades each having an abutment moving radially upon swinging of the blades, a collar rotatable on said

60 shaft and having a pair of stops extending for a portion of the circumferential extent thereof for engagement with said abutments, said collar when rotated to one position bringing said stops into positions to be engaged by said abutments to hold

65 the blades at one particular pitch and when rotated to another position moving said stops out of the path of movement of said abutments to allow said blades to swing in a manner to have a different pitch, said collar and hub having facing surfaces, locking means formed on said surfaces for holding said collar and hub for relative rotational movement and means for urging

70 relative movement between said collar and hub to bring said surfaces toward one another.

7. In a propeller, a driven shaft, a hub rotat-

7
ably and axially movable on said shaft, blades pivoted to said hub, the pivots of said blades being positioned so that the pitch of the blades varies upon swinging of the blades, said blades each having an abutment moving radially upon swinging of the blades, a collar rotatable on said shaft and having a plurality of stops disposed at different distances from the axis of said shaft, said stops being located at different localities circumferentially of said collar and being adapted to selectively engage said abutments to hold the blades in various adjusted positions and means for locking said collar from relative movement with respect to said hub.

8. In a propeller, a driving member, a driven member, blades movably supported on said driven member, releasable driving means between driving member and driven member and including a movable part adapted upon movement in one direction to oppose release of the driven member, adjusting means for said blades including a stop, locking means for holding said stop from movement and including a movable part movable along substantially the path of movement of said first

named part, and upon movement in a direction opposite to the denoted direction of movement of said first named part restraining adjusting movement of said stop and resilient means acting between said parts and urging movement thereof in the respective denoted directions.
